1,937,307

SAFETY RAZOR BLADE SHARPENER

Walter D. Bishop, Kansas City, Kans., assignor
of one-third to Harold Brown, Kansas City,
Kans.

Application August 3, 1931. Serial No. 554,784

10 Claims. (Cl. 51—161)

My invention relates to a device for sharpening razor blades in a quick and effective manner, and more particularly the double-edged razor blades for safety razors. During the sharpening operation the blade is carried around with one side of each edge in contact with the inner surface of a tubular or cylindrical sharpening element. At a certain point in each circuit the blade is carried across the interior of the sharpening element until the opposite side of each edge contacts with the inner surface of said sharpening element, when the rotary movement is resumed. In other words, during one circuit of the blade one side of each edge is subjected to the sharpening action and during each alternate revolution the other side of each edge is subjected to the sharpening action. The bringing of first one side and then the other of the edges into contact with the sharpening element is automatic and requires no attention on the part of the operator.

In order that the invention may be fully understood, reference will now be had to the accompanying drawing, in which:

Fig. 1 is a front elevation of the sharpening device.

Fig. 2 is a vertical cross section on line 2—2 of Fig. 1.

Fig. 3 is a horizontal cross section on line 3—3 of Fig. 2.

Fig. 4 is a broken vertical section of the device on line 4—4 of Fig. 2.

Fig. 5 is a broken side elevation of the device.

Fig. 6 is an exploded perspective view of the blade holder.

Referring in detail to the different parts, 2 designates a tubular or cylindrical sharpening element which consists of glass or other suitable material. The inner surface of the sharpening element 2 may be left smooth for use in stropping the razor blade A, or it may be roughened in any suitable manner to act as a hone.

The ends of the sharpening element 2 are closed by heads 4 provided with peripheral flanges 6 and consisting preferably of resilient sheet metal so that said flanges 6 will frictionally engage the ends of the sharpening element 2 and thus prevent it from turning with the razor blade during the sharpening operation. The sides of the heads 4 have corresponding segmental channels 8 and transverse channels 10 formed therein for the purpose of guiding a blade-holder 12 in its circuit and causing it to press the blade A against the inner surface of the sharpening element 2. The ends of the channels 8 and 10 in each head 4 communicate with each other as

best shown by Fig. 2, so that the blade-holder may readily pass from one to the other.

The blade-holder 12 consists of a pair of clamp members 14 each of which is provided at its reduced terminals with flanges 16 adapted to travel in the respective channels 8 and 10. One of the clamp members 14 is provided with headed studs 17 adapted to pass through the medial openings of the razor blade A and a plurality of key-hole slots 18 in the companion clamp member, which latter is then moved longitudinally to carry the reduced ends of the slots 18 beneath the heads of the studs 17 and thus firmly secure the two clamp members together.

22 designates a rotatable carrier for carrying the blade-holder 12 around in the sharpening element 2. The carrier 22 consists of a shaft 24, a pair of arms 26, and a pair of arms 28. The arms 26 and 28 project laterally from the shaft 24 which is provided at its ends with trunnions 30 mounted in bearings 32 at the central portions of the heads 4. Motion is imparted to the shaft 24 by suitable means such, for instance, as a manually controlled crank 34 secured upon one of the trunnions 30.

In order that the blade-holder 12 may be readily placed in position in the carrier 22, I provide one of the heads 4 with a door 36 which is preferably connected to said head by hinge means 38. The door 36 may be held in closed position by either frictionally engaging the outer periphery of the sharpening member 2, or by springs 40 associated with the hinge means 38.

In practice the blade A is secured in position between the clamp members 14 of the blade-holder 12, which latter is then placed between the arms 26 and 28, care being taken to locate the flanges 16 in the channels 8 or 10. The crank 34 is then rotated and in turn rotates the carrier 22. As the flanges 16 travel in the channels 8 those flanges which bear against the inner segmental walls 20 of said channels cause the blade-holder 12 to press the sides B of the blade A against the interior of the sharpening member 2, Fig. 2, to facilitate the sharpening operation.

When the flanges 16 reach the adjacent end of the channels 10 they are caused to enter the latter by the outer walls 42 of said channels and the arms 26 of the carrier 22. Continued pressure of the arms 26 against the blade-holder 12 causes the flanges 16 to travel through the channels 10 and into the right end (Fig. 2) of the channels 8. As the flanges 16 travel through the channels 10 the blade-holder is held in the

dotted line position, Fig. 2, by said flanges 16 and the arms 26 and 28. As the blade A approaches the right end of the channels 8 the sides C of its edges are forced into frictional contact with the inner surface of the sharpening element 2.

The flanges 16 afford means whereby the blade-holder 12 may be grasped when inserting or removing it from the interior of the sharpening element 2.

From the foregoing it will be understood that the sides B of the razor blade A will be held in engagement with the interior of the sharpening element 2 during one circuit of the carrier 15 22 while the opposite sides C will be held in engagement with the sharpening element 2 during each alternate circuit, so that on completion of the sharpening operation both sides B and C will have received like treatment without requiring the operator to reverse or otherwise manipulate the blade A during the sharpening operation.

While I have shown one form of the invention it is to be understood that I reserve all rights to such other forms and modifications as properly fall within the spirit and scope of the invention as claimed.

Having thus described my invention, what I claim and desire to secure by Letters Patent, 30 is:

1. A razor blade sharpening device consisting of a curved sharpening element, a blade holder for holding a blade against the concave surface of said sharpening element, a rotatable carrier for carrying the blade around in the sharpening element, supporting means for said carrier, flanges on the blade holder, and guide channels in which said flanges travel and which cooperate with the blade holder in presenting opposite sides of the blade to the concave surface.

2. A razor blade sharpening device consisting of a cylindrical sharpening element, heads mounted upon the ends of said sharpening element and provided with segmental and transverse channels, a blade holder for holding a blade against the inner surface of said sharpening element and having its ends arranged to travel in said grooves to alternately present the sides of the edges of the blades to said sharpening element, and suitably supported means for actuating said blade holder.

3. A razor blade sharpening device comprising a curved sharpening element, a holder for holding the razor blade in frictional engagement with the concave surface of said sharpening element, rotatable means for carrying said blade holder in a circuit within the sharpening element, and guide means mounted on the sharpening element adapted to coact with the blade holder and said rotatable means in holding one side of the razor blade against the concave surface of the sharpening element and in shifting said razor blade to carry its opposite side into frictional engagement with said concave surface during each circuit of the blade holder.

4. A razor blade sharpening device comprising a curved sharpening element, a blade holder comprising two clamp members for holding the razor blade in frictional engagement with the concave surface of said sharpening element, rotatable means for carrying said blade holder in a circuit within the sharpening element, and guide means mounted on the sharpening element adapted to coact with the blade holder and said rotatable means in holding one side of the razor

blade against the concave surface of the sharpening element and in shifting said razor blade to carry its opposite side into frictional engagement with said concave surface during each circuit of the blade holder.

5. A razor blade sharpening device comprising a curved sharpening element, a holder for holding the razor blade in frictional engagement with the concave surface of said sharpening element, rotatable means including spaced arms for carrying said blade holder in a circuit within the sharpening element, and guide means mounted on the sharpening element adapted to coact with the blade holder and said rotatable means in holding one side of the razor blade against the concave surface of the sharpening element and in shifting said razor blade to carry its opposite side into frictional engagement with said concave surface during each circuit of the blade holder.

6. A razor blade sharpening device comprising a curved sharpening element, a blade holder for holding the razor blade in frictional engagement with the concave surface of said sharpening element, rotatable means for carrying said blade holder in a circuit within the sharpening element, a crank for driving said rotatable means, and guide means mounted on the sharpening element adapted to coact with the blade holder and said rotatable means in holding one side of the razor blade against the concave surface of the sharpening element and in shifting said razor blade to carry its opposite side into frictional engagement with said concave surface during each circuit of the blade holder.

7. A razor blade sharpening device comprising a curved sharpening element, heads on the ends of said sharpening element, a holder for holding the razor blade in frictional engagement with the concave surface of said sharpening element, a rotatable member journaled in the heads and provided with two pairs of spaced arms adapted to carry the blade holder in a circuit within the sharpening element, means for operating said rotatable member, and guide means carried by the heads and adapted to coact with said rotatable member and the blade holder in holding one side of the blade against the concave surface of the sharpening element and in shifting the blade to bring its opposite side into frictional contact with said concave surface during each circuit of the blade holder.

8. A razor blade sharpening device comprising a cylindrical sharpening element, heads mounted upon the ends of said sharpening element and provided with communicating curved and transverse guide channels, a holder for holding the razor blade in frictional engagement with the concave surface of the sharpening element and having its ends projecting into said guide channels, and rotatable means for carrying the blade holder in a circuit within the sharpening element and coacting with said holder and the guide channels in holding one side of the razor blade against the concave surface of the sharpening element and in shifting said razor blade to carry its opposite side into frictional engagement with said concave surface during each circuit of the blade holder.

9. A razor blade sharpening device comprising a cylindrical sharpening element, heads mounted upon the ends of said sharpening element and provided with communicating curved and transverse guide channels, a holder for holding the razor blade in frictional engagement with the concave surface of the sharpening element and in shifting said razor blade to carry its opposite side into frictional engagement with said concave surface during each circuit of the blade holder.

concave surface of the sharpening element, flanges on the ends of said blade holder and projecting into the guide channels, and rotatable means for carrying the blade holder in a circuit within the sharpening element and coacting with said holder and the guide channels in holding one side of the razor blade against the concave surface of the sharpening element and in shifting said razor blade to carry its opposite side into frictional engagement with said concave surface during each circuit of the blade holder.

10. A razor blade sharpening device comprising a cylindrical sharpening element, heads mounted upon the ends of said sharpening element and provided with communicating curved and transverse guide chan-

nels, a holder for holding the razor blade in frictional engagement with the concave surface of the sharpening element and having its ends projecting into said guide channels, said blade holder being removable through an opening in one of the heads, a door for closing said opening, and rotatable means for carrying the blade holder in a circuit within the sharpening element and coacting with said holder and the guide channels in holding one side of the razor blade against the concave surface of the sharpening element and in shifting said razor blade to carry its opposite side into frictional engagement with said concave surface during each circuit of the blade holder.
